UNITED STATES PATENT OFFICE.

GEORGE W. SUMNER, OF DORCHESTER, NEBRASKA, ASSIGNOR OF THREE TWENTY-FIFTHS TO RUSSELL MOOBERRY, THREE TWENTY-FIFTHS TO THOMAS GRAY, THREE TWENTY-FIFTHS TO ROBERT C. PANTER, AND THREE TWENTY-FIFTHS TO J. W. BYERS, ALL OF DORCHESTER, NEBRASKA.

TELEPHONE ATTACHMENT.

Application filed October 11, 1921. Serial No. 507,008.

To all whom it may concern:

Be it known, that I, GEORGE W. SUMNER, a citizen of the United States, residing at Dorchester, in the county of Saline and State of Nebraska, have invented certain new and useful Improvements in Telephone Attachments, of which the following is a specification.

The present invention appertains to improvements in attachments for telephones designed for cooperation with the receiver hook of the ordinary conventional telephone equipment, and by means of which said hook may be held temporarily in a position which prevents closing of the transmitter circuit, for the purpose of saving the battery current and eliminating the noises likely to interfere with conversations over the talking circuits of the line.

20 The invention is devised primarily for use in conjunction with selective ringing or party line systems, where the various subscribers are able to listen in upon the conversations of the talking parties.

25 As is well known, much annoyance is occasioned by those subscribers who listen in because of the noises in the rooms of those subscribers who are listening only, due to the fact that these are transmitted through the transmitters of the various instruments, the transmitter circuits all being closed. In addition to this disadvantage there is a necessary drain upon the batteries of the local instruments because of

35 the closing of the battery circuit which is not in use, and it is therefore the object of this invention to provide a simple attachment which may be readily arranged so as to limit the movement of the receiver hook 40 and permit the latter to close only the listening circuit when the party desires to listen in upon the line only, the attachment including means for releasing the receiver hook to permit it to complete its normal full move-

45 ment and thereby close the talking circuit at the will of the operator of the local telephone.

50 The above and such other objects as may hereinafter appear are attained by the novel construction, combination and arrangement

of parts to be hereinafter specifically described and claimed.

Reference will now be had to the accompanying drawings forming a part of this specification, wherein:

55 Figure 1 is a side elevation showing my invention or attachment applied in cooperative relation to the receiver hook of a conventional telephone instrument.

Figure 2 is a side elevation of the construction shown by Figure 1.

Figure 3 is a sectional view on the line 3-3 of Figure 1.

Throughout the following detailed description and on the several figures of the drawing, similar parts are referred to by like reference characters.

65 In the drawing 1 designates the side board of the telephone instrument box through which the receiver hook 2 projects. This hook is fulcrumed at 3 and is provided with a laterally extending arm 4 arranged to coact with the free end of the hook switch spring 5. This spring carries a button 6 arranged to coact with the series of circuit closing members or leaves 7.

75 The foregoing construction is of a conventional type and it will be understood by those skilled in the art to which the invention relates that when the receiver is positioned upon the hook 2 the spring 5 is held out of coacting relation to the circuit contact members 7 adjacent thereto in which position both the line and talking or transmitter circuits are open. When the receiver is displaced from the hook 2 the spring 5 brings the first two of the circuit closing leaves into contact, closing the line circuit, this taking place upon the partial normal movement of the hook 2 and upon the completion of the movement of this hook the third circuit closing member is impinged, thus closing the primary or transmitter circuit.

85 90 95 The attachment which forms the subject-matter of this invention comprises a hook member which is pivotally mounted upon the side board 1 by a screw 8 adjacent to the receiver hook 2 and said attachment is composed of the relatively fixed section 9 to 100

2
which is connected the adjustable section 10 having a lateral bent extremity 11 arranged to engage over the receiver hook 2. To the fixed section 9 is connected an actuating arm 12 the outer end 13 of which is bent at right angles to form a thumb piece. The arm 12 is connected to the hook member of the attachment by means of the set screw 14 which also constitutes the adjusting means for the adjustable section 10. Near the outer end, the arm 12 is provided with a guide slot 12' through which the screw 15 extends into the board 1 and a spiral spring 16 is connected at one end to this stationary screw and at its other end to the screw 14 for the purpose of placing tension upon the hook member normally holding the extremity 11 across the path of movement of the receiver arm 2.

20 From the foregoing it will be obvious that when the party desires to listen in upon the conversation without talking over the telephone line, he removes the telephone receiver from the hook 2 and the latter is caught at an intermediate position by the hook 11 which is so arranged that it will intercept the receiver hook at a point where only the first two contact members are brought together. The listening circuit being closed, the conversation may readily be heard, but since the talking circuit is open the noises in the room of the instrument are prevented from being transmitted through the transmitter, and furthermore, the battery current is not used. When it is desired to talk over the instrument, the operator presses upon the end of the arm 12 thereby shifting the hook 11 rearwardly and disengaging the receiver hook so as to permit it to move its normal full swing bringing the transmitter circuit into operation. In this position the end of the hook 11 is held in contact with the side of the receiver hook and immediately the receiver is hung upon said hook, the downward movement of the latter will permit the hook member of the attachment to again assume its normal position overlying the path of upward movement of said hook. Thus it will be seen that the attachment is always in position for performing its function but may readily be displaced whenever it is desired that the talking circuit shall be closed.

55 One of the important features of this simple attachment is the provision for adjustment. To this end it is only necessary to attach the device by the screw 8 in a reasonably approximate position beneath the receiver hook and the section 10 is then adjusted by the screw 14 so as to occupy a position which will permit the movement of the receiver hook only to that point where it will insure of the closing of the line circuit. The set screw 14 is then tightened 60 and the attachment will remain adjusted so

far as this particular instrument is concerned.

Having thus described my invention, what I claim as new and desire to secure by Letters Patent is:

70 1. A telephone attachment of the class described, comprising a pivotally mounted stop member arranged adjacent to the receiver hook of the telephone instrument and adapted to be swung into the path of movement of the receiver hook to intercept the movement thereof, and a slide connected to the said stop member for moving the same.

75 2. A telephone attachment of the class described including a hook member pivotally mounted adjacent to the receiver hook of the telephone instrument and adapted to be moved into the path of the said receiver hook to intercept the movement thereof when the receiver is disengaged from the receiver hook, tension means normally tending to swing the hook member into the path of the receiver hook, and an operating member mounted upon the telephone instrument and operatively connected with the hook member for moving the latter against the action of the tension means into inoperative position.

80 3. A telephone attachment of the class described comprising a hook member adapted to be mounted adjacent the receiver hook of the telephone instrument, said hook member embodying an adjustable section with which said receiver hook is adapted to impinge, and an actuating slide connected to said hook member at an intermediate point for shifting the latter about its pivotal mounting.

85 4. An attachment for telephones of the class described comprising a sectional hook member adapted to be pivotally mounted adjacent to the receiver hook of the telephone instrument, spring means normally tensioning the hook member to hold it in a position intercepting the path of movement of the receiver hook, an actuating arm co-acting with said hook member, and guide means for said actuating arm.

90 100 5. A telephone attachment of the class described including a movably mounted hook member, and yielding means normally tending to swing the same into the path of movement of the receiver hook of the telephone instrument to prevent a full movement of the said receiver hook when the receiver is lifted therefrom, said hook member being movable away from the path of the receiver hook when full movement thereof is desired and the nose of the hook member abutting yieldably against the receiver hook when the latter has reached the limit of its movement.

105 110 115 120 125 6. A telephone attachment of the class described, comprising a swinging arm, a hook member having the shank thereof adjustably

connected to the swinging arm and adapted to be moved into the path of the receiver hook of the telephone instrument to intercept the movement of the said hook when the receiver is removed therefrom, a fastening member adjustably connecting the shank of the hook member to the swinging arm, and an actuating member operatively connected to said hook member by the said fastening member for swinging the arm and 10 hook member.

In testimony whereof I affix my signature.

GEORGE W. SUMNER.
